[57] CLAIM

The ornamental design for a figurine of an orangutan, substantially as shown.

DESCRIPTION

FIG. 1 is a side perspective view of a figurine showing
our new design;

FIG. 2 is an opposite side perspective view showing the

FIG. 3 is a front end elevational view of FIG. 1;

FIG. 4 is a rear end perspective view of FIG. 1; and
FIG. 5 is a top plan view of FIG. 1.
